The ornamental design for an asymmetric light fixture, as shown and described.

DESCRIPTION

FIG. 1 is a perspective view of a first embodiment of my design for an asymmetric light fixture;

FIG. 2 is a front view of the asymmetric light fixture shown in FIG. 1;

FIG. 3 is a right side view of the asymmetric light fixture shown in FIG. 1;

FIG. 4 is a left side view of the asymmetric light fixture shown in FIG. 1;

FIG. 5 is a top plan view of the asymmetric light fixture shown in FIG. 1;

FIG. 6 is a bottom plan view of the asymmetric light fixture shown in FIG. 1;

FIG. 7 is a rear view of the asymmetric light fixture shown in FIG. 1;

FIG. 8 is a perspective view of a second embodiment of my design for an asymmetric light fixture that is a mirror image of the embodiment shown in FIG. 1, the other views of the second embodiment being respective mirror images of the views shown in FIGS. 2–7;

FIG. 9 is a perspective view of a third embodiment of my design for an asymmetric light fixture;

FIG. 10 is a front view of the asymmetric light fixture shown in FIG. 9;

FIG. 11 is a right side view of the asymmetric light fixture shown in FIG. 9;

FIG. 12 is a left side view of the asymmetric light fixture shown in FIG. 9;

FIG. 13 is a top plan view of the asymmetric light fixture shown in FIG. 9;

FIG. 14 is a bottom plan view of the asymmetric light fixture shown in FIG. 9;

FIG. 15 is a rear view of the asymmetric light fixture shown in FIG. 9; and,

FIG. 16 is a perspective view of a fourth embodiment of my design for an asymmetric light fixture that is a mirror image of the embodiment shown in FIG. 9, the other views of the second embodiment being respective mirror images of the views shown in FIGS. 10–15.

The broken lines shown in the various figures are for illustrative purposes only and form no part of the claimed designs.
